Landphere & Remington,
Spoke Machine.

Nº 12,459.

Patented Feb. 27, 1855.

UNITED STATES PATENT OFFICE.

ASA LANDPHERE, OF ALBION, PENNSYLVANIA, AND S. REMINGTON, OF ILION, NEW YORK.

SPOKE-MACHINE.

Specification of Letters Patent No. 12,459, dated February 27, 1855.

To all whom it may concern:

Be it known that we, ASA LANDPHERE, of Albion, in the county of Erie and State of Pennsylvania, and SAMUEL REMINGTON, of Ilion, in the county of Herkimer and State of New York, have invented certain new and useful Improvements in Machinery for Cutting Spokes and other Articles of Irregular Form; and we do hereby declare that the following is a full, clear, and exact description of the same, reference being had to the accompanying drawings, forming part of this specification, in which—

Figure 1, is a side elevation of a machine for cutting spokes, constructed according to our improvements. Fig. 2, is a plan of the same. Fig. 3, is a transverse vertical section of the same in the dotted line, x, x , of Fig. 1. Fig. 4, represents the profiles of the two sets of cutters.

Similar letters of reference indicate corresponding parts in the several figures.

The nature of our invention consists in planing the stuff longitudinally, by means of two sets of rotary cutters, which are arranged and operated in the manner herein-after described.

A, in the accompanying drawing, is the main frame of the machine supporting the fixed horizontal ways, a, a , upon which the carriage, B, rests. The carriage, B, is furnished with a fixed head, C, and a movable head, D, which are furnished with dogs, c , and d , between which the piece of stuff, F, to be operated upon, is held. These dogs are of cylindrical form for the greater portion of their length, and are both in line. The dog, c , has a head of such form, that it will not allow the stuff to turn independently of it, and it is furnished with a spur wheel, b , which gears with another spur wheel b' , of similar size, on a shaft, E, which is arranged longitudinally in the carriage, and furnished with a handle, e , to turn it, and thereby turn the dog, c . The handle, e , is made flexible, and furnished with a pin, f , on its inner face, which is capable of entering either of two holes (not shown) in the end of the carriage, and thereby holding the shaft secure from turning, and also securing the dog, c , and the stuff. The carriage, B, is furnished with profile plates, g, g , whose outer edges are of the proper form, to direct the lateral movements of the cutters to cause them to give the desired longitudinal pro-

file to the sides, and other profile plates, g', g' , whose upper edges are of the proper form to direct the vertical movements of the cutters, to cause them to give the desired longitudinal profile to the top and bottom of the article to be produced, all bolted to the sides of the carriage. At about the middle of the length of the carriage, there is a transverse shaft, G, which works in bearings in the sides, and is furnished with a broad crank, G', which is capable of being turned upwards to form a rest or support for the stuff midway between the dogs, and prevent it bending. This shaft is furnished outside the carriage with a spring lever, h , which has a tooth on its inner face, to engage in a fixed ratchet sector, i , secured to the carriage, and thereby hold the rest, G', up in its place.

Near the back end of the main frame, or that end at the left hand of Figs. 1, and 2, is a frame which we will term the cutter frame, composed of two standards, H, H, and a cross piece, I, which extends all across the machine. This frame is bolted firmly to the main framing, and carries two gates, J, J', which swing freely side by side on the horizontal transverse pivots, j, j' , by which they are attached to the cutter frame. The gate, J, has suitable bearings, k, k , to receive a horizontal transverse shaft, K, which carries a series of cutters, L; and the gate, J', has bearings, k, k , to receive a horizontal shaft, K', which carries a series of cutters, L'. Both these shafts are free to move to a certain extent longitudinally in their bearings, and are attached by loose arms, N, N, to rods, M, and M', which are parallel with them, and slide longitudinally in bearings in their respective frames. These rods are so connected with the shafts as to move longitudinally with them, and are surrounded by coiled springs, l, l' , which are so applied to them as to force the shafts toward the center of the machine. The rods, M, M', have arms, m, m' , which hang downward, and these arms are forced by the springs, l, l' , into contact with the profile plates, g, g , on the carriage, B. The gates are also provided with screws, O, O', which work in female screws in their front ends, and have their points protruding through the bottom, and resting upon the profile plates, g, g' . The cutters are of such form that the figure described by the revolution of either set will have a profile of which the part farthest

from the center of the machine, corresponds in form to one quarter of the transverse section of the rounded part of the spoke, and then extends toward the center of the machine in a straight line. This is shown in Fig. 4, where the profiles described by the revolutions of the two sets of cutters are shown. Those parts of the profiles between n, n , correspond in form with one quarter of the rounded part of the spoke and the parts between n, o , are straight. The gate, J' , is made longer than the gate, J , in order to bring the cutter shaft, K' , in advance of that K , and allow the two sets of cutters to work clear of each other. In rear of the gates, J, J' , there is another horizontal cutter shaft, P , which runs in fixed bearings in the standards, H, H , and carries a disk, P' , furnished with cutters p, p , which cut sideways. This cutter shaft is allowed to move longitudinally to a certain extent, in its bearings, and is connected by a loose arm, Q , with a rod, R , which is parallel with it. This rod is allowed to slide longitudinally in bearings in the standards, H , and is so connected to the shaft, that both move longitudinally together. It has a coiled spring, q , applied to it in such a way as to push it from that side of the machine shown in Fig. 1, and thus push the cutter shaft, P , in the same direction and cause it to carry the cutters toward their work. The rod, R , has another arm, r , which is held at suitable times by the spring, q , in contact with the curved edge of a plate, s , which is attached to the carriage, B .

The movements of the several cutters and the carriage, B , are all derived from the main shaft, S , which receives rotary motion from any prime mover, through a belt leading to the driving pulley, T . The swinging cutter shafts, K, K' , receive rotary motion from the shaft, S , by means of belts, u, u , see Fig. 1 which run from pulleys U, U' , to pulleys, U', U' , on the said cutter shafts. The tension of these belts serves to hold down the swinging gates, and keep the adjusting screws, O, O' , in contact with the profile plates, g', g' . The cutter shaft, P , receives rotary motion through a belt, v , running over its pulley, V' , from a pulley, V , on the main shaft. The carriage, B , receives a backward motion on the ways, a, a , in the direction from right to left of Figs. 1, and 2, to carry the stuff in contact with the cutters, from a small pulley, W , on the main shaft from which a belt, w , runs to a pulley, t , on a shaft, X , at the front end of the machine. This shaft carries another pulley, Y , from which a belt, y , runs to a pulley Z' , on a shaft, Z , which carries a pinion, 5 , gearing with a spur wheel, 6 , on a shaft, 7 , which carries a pinion, 8 , shown dotted in Fig. 1 gearing with a rack, 9 , under the carriage. The shaft, Z , has one

end supported and running in a bearing in a lever, 10 , which is moved up and down to throw the pinion, 5 , in and out of gear. When the pinion is to be thrown in gear, the lever requires to be raised, and the lever is then supported on a step on a spring, 12 , which is also attached to a shipper lever, 13 , moving horizontally on the top of the main frame. The shipper lever is acted upon to throw the step of the spring, 12 , from under the lever, 10 , to allow the pinion, 5 , to fall out of gear by an adjustable clamp, 14 , attached to the carriage. The carriage is run forward, or from left to right of Fig. 1, after the cutters have done their work, at a quicker speed than it is run back, to effect the cut, by means of a belt, 15 , running from a pulley, 11 , on the shaft, X , to a pulley 16 , on the shaft 7 . The pulley, 11 , is loose on its shaft, and is coupled and uncoupled by an arrangement of mechanism, which is not visible in the views which are shown of the machine, and which being unimportant, is not in any other place represented.

The operation of cutting a spoke is conducted in the following manner. The carriage is run out to the front end of the machine, the stuff secured between the dogs, c, d , and the rest, G' , brought up to support it. The main shaft is then set in motion, the pinion, 5 , thrown in gear with the wheel, O , and the wheel, 11 , uncoupled from the shaft, X . The cutters then receive rapid rotary motion, and the carriage is slowly moved backwards. When the stuff first arrives under the cutters, L, L' , both these sets of cutters are forced away from the center of the machine, by the pins, m, m' , and profile plates, g, g , and only the straight parts, n, n , of the cutters are allowed to come in contact with the stuff, as shown in Fig. 4, and plane the top flat, as the first part which is acted upon is intended to form the shoulder of the spoke; but as the carriage moves on the pins, m, m' , are allowed by the plates to approach the center of the machine, and the curved parts of the cutters come into operation. The profile plates, g, g , direct the movements of the cutters laterally to the stuff, and the ways, g, g' , direct their vertical movement, and thus regulate the form of the longitudinal profile of the stuff. The curved parts of the two sets of cutters plane the upper half of the spoke, each set of cutters planing one quarter. One side of the shoulder is planed by the cutters, p, p , on the disk, P' whose position is regulated by the arm, r , and the profile plate, s , which also serve to guide the disk and cutters out of the way of the wheels, b, b' , and any appendages of the carriage with which they might otherwise come in contact. When the whole length of the stuff has passed the cutters, L, L' , the clamp 14, which has been pre-

viously properly adjusted, comes in contact with the shipper lever, and sets free the lever, 10, which falls and lets the pinion, 5, out of gear and thereby stops the carriage. The attendant, then, by means of the proper mechanism, couples the pulley, 11, with the shaft, X, and the carriage returns quickly forward. When the carriage stops, the handle, e, is turned half way round, which turns the stuff half way round, and brings the unfinished part to the top. The attendant next raises the lever, 10, and brings the pinion, 5, in gear with the wheel, O, and the carriage runs back again, and causes the half of the stuff now uppermost, to be submitted to the same operation as was performed on the other half during the previous backward movement of the machine, and the opposite side of the part which first arrives at the cutters, to be squared off by the cutters, p, p. The spoke is now complete, and when the carriage has run forward, it may be taken out, and another piece of stuff inserted between the dogs.

The operation of cutting any other article,

is conducted in a similar manner to that of cutting a spoke. The difference in form is produced by using cutters and profile plates of different form.

This machine performs its work very perfectly, owing to the cut being made lengthwise of the grain of the stuff, in which respect it differs from most machines now in use for cutting similar articles.

Having thus fully described the nature of our invention what we claim therein as new and desire to secure by letters patent is—

The dressing of spokes by means of a series of revolving cutters whose edges present an oblique profile in part of the spoke, when said cutters are so arranged on their shafts as to reduce the spoke in narrow longitudinal sections, by which means much more smooth work is obtained than when the cutters reduce the spoke at one single operation as set forth.
